Vincent J. Whitney

BY *John A. Baumith*
ATTORNEY

UNITED STATES PATENT OFFICE.

VINCENT J. WHITNEY, OF SAN FRANCISCO, CALIFORNIA.

WINDOW SUPPORT.

Application filed December 1, 1922. Serial No. 604,379.

To all whom it may concern:

Be it known that I, VINCENT J. WHITNEY, a citizen of the United States, and a resident of San Francisco, in the county of San Francisco and State of California, have invented a certain new and useful Improvement in Window Supports, of which the following is a specification.

This invention relates to means for supporting a window in such a manner that it may be swung open and free from the casing at both sides whereby it may be cleaned on the outside without the necessity of approaching it from the exterior of the building.

It is the object of my invention to provide a device of the character indicated that will be smooth and positive in its operation, and wherein a simple and highly efficient means is provided for securing the parts of the device against movement when extended.

It is a further object of my invention to provide a device of the character indicated that will be simple in operation, economical to manufacture, preferably assembled and easily installed and highly efficient in its practical application.

In the drawing:—

Figure 1 is a plan view of my improved window support showing the manner of mounting on the sill with the window extended, parts being broken away.

Figure 2 is a plan view of the same showing the window closed, parts being broken away.

Figure 3 is a cross-sectional view taken on line 3—3 of Figure 1.

Figure 4 is a detailed plan view of the window holding shoe.

Referring more particularly to the drawing, Figs. 1, 2, I show a window casing at 1—2. The portion 1 of said casing has a track member 3 mounted thereon, as shown, by means of screws 4 which have their heads counter-sunk below the upper surface 5 of said track 3. The track member 3, Fig. 3, has one of its edges turned upwardly at right angles thereto as at 6, thence inwardly a distance as at 7 and then downwardly as at 8 thus forming a channel 9 having an opening as 10 on the inner side thereof as shown and opposed to and parallel with the track surface. At 11—11 are orifices passing through track member 3 for purposes hereinafter disclosed.

At 12, Figs. 1, 2, is shown a window sup-

porting plate having orifices 13 passing therethrough for the purpose of securing said plate to the under side of a window sash 14, shown in dotted lines, by means of screws 15 which have their heads countersunk flush with the under surface of plate 12 as shown in Figure 3. The ends of plate 12 have depending portions 16 through which orifices 17 pass, their upper portions 65 being flared as at 18.

I show at 19, Fig. 3, a shoe member having a double thickness as at 20 and a boss formed thereon as at 21 through an orifice 22 passes. The shoe 19, Fig. 4, has a portion 25 extending in a direction opposite to the edge 26, and has its under surface 27 on the same plane as the under surface 28 of portion 20 of member 19. The surfaces 27—28 are formed to slide over track 3 and the outer 75 edge 29 of portion 25 is bent upwardly at right angles to the plane of surfaces 27—28 so as to slide freely in the channel 9. The portion 25 passes through the orifice 10 as shown in section in Figure 3. The ends of 80 the upturned portion 29, Fig. 4, may be bent at right angles thereto to form fingers 30 of a length of lesser proportions than the width of channel 9. At 31 is shown an arcuate spring member which may be placed between the fingers 30 of portion 29 of member 19. The length and curvature of the same are such as to press the portion 29 against the depending channel wall or portion 8 of track 3, as shown, thus causing 85 sufficient frictional contact between track 3 and the shoe 19 to hold the same and window sash in any position in which it may be placed along the track while at the same time allowing the shoe to be freely moved 90 along said track and the window correspondingly adjusted.

Pivotedly mounted upon track 3 at one end thereof is a link 32 held in place by rivet 33 passing through opening 11 in the 100 said track. The outer end of the arm 32 is pivotally mounted upon the under side of plate 12 on depending portion 16 by means of rivet 34 passing through orifice 17 in said plate.

The length of the track 3 is determined by the length of plate 12 and arm 32 as is shown in Figure 2 which shows the several parts in their respective positions when the window is closed.

If it is desired to open the window the shoe 19 is slid along on track 3 by push-

ing on the window sash which causes a turning movement of plate 12 on shoe 19, and arm 32, due to its length and connections causes the shoe to slide on the track, until the portion 25 strikes the link 32 at a point as shown at 35 in Figure 1. The window is now at right angles to the casing so that the outer surface of the same may be easily cleaned.

10 The window is prevented from rattling or from movement in either direction, due to air currents, by means of spring 31 which as stated, before, causes a decided frictional contact between the shoe and the track 15 which holds the window in any position desired. This is more readily accomplished by having the device placed on both the lower and upper rails of the sash which allows the window to be swung open or shut 20 quickly and easily by avoiding the uneven leverage exerted on the mechanism when the window sash is grasped at its edge opposite that to which the shoe is attached.

Thus it can be seen that I have provided 25 a device of the character indicated which will allow a window to be swung open and free from the casing at both sides whereby it may be cleaned on the outside from the interior of the building. The device is smooth and 30 positive in operation and provided with a simple means for securing the several parts against movement when extended, as well as being easily installed upon any window and being highly efficient in its practical 35 application.

It is to be understood, of course, that while I have herein shown and described one particular embodiment of my invention, changes in form, proportion, construction 40 and method of operation may be made within the scope of the appended claims.

I claim:—

1. A window support comprising a track, a shoe slidably connected thereto, a plate 45 pivotally mounted on said shoe, a link pivotally connected to said plate and track and an extension carried by said shoe and engageable with the end of the link connected to said track.

2. A window support comprising a track, a shoe having a recess formed therein slidably mounted in said track, a plate pivotally mounted on said shoe, a link pivotally connected to said plate and track, and an 55 outwardly directed arcuate spring member mounted in the said recess in said shoe to slidably engage said track.

3. A window support comprising a track,

a shoe having a recess formed therein slidably mounted in said track, a plate pivotally mounted on said shoe, a link pivotally connected to said plate and track, and an arcuate spring member removably mounted in the said recess in said shoe to slidably engage said track. 60 65

4. A window support comprising a track having a surface arranged in opposed relation to the edge of the supported window and carrying a channel in opposed and parallel relation to said surface, a shoe slidably mounted in said channel, a plate pivotally mounted on said shoe to move in parallel relation to said surface, and a link pivotally connected to said plate and track. 70

5. A window support comprising a track 75 member having a surface arranged in opposed relation to the edge of the supported window and carrying a channel in opposed and parallel relation to said surface, a shoe slidably mounted in said channel, a link pivotally mounted at a fixed point on said track to swing in a plane parallel to said surface, and a plate pivotally connected to said link and said shoe to swing in a plane parallel to said surface. 80 85

6. A window support comprising a track, a shoe slidably connected thereto, a plate pivotally mounted on said shoe, a link pivotally connected to said plate and track and engageable with said sliding shoe. 90

7. A window support comprising a track, a shoe slidably connected thereto, a plate pivotally mounted on said shoe, a link pivotally connected to said plate and track and said shoe engageable with a stop for limiting its movement on said track. 95

8. A window supporting unit comprising a track, a shoe slidably connected thereto, a plate pivotally mounted on said shoe, a link pivotally connected to said plate and track and means for stopping movement of said shoe. 100

9. A window supporting unit comprising a track, a shoe slidably connected thereto, a plate pivotally mounted on said shoe, and 105 adapted for engagement with the sash of a swinging window, and a link pivotally connected to said plate and track.

10. A window supporting unit comprising a track, a shoe slidably connected thereto, said shoe being adapted for resilient and 110 slidable engagement with said track, a plate pivotally mounted on said shoe and a link pivotally connected to said plate and track.

VINCENT J. WHITNEY.
